FLOW-CONTROLLING MECHANISM FOR CRUSHER-FEEDERS

Arthur G. Nickle, Saginaw, Mich., assignor to Nickle Engineering, Saginaw, Mich.

Application May 31, 1950, Serial No. 165,300

3 Claims. (Cl. 241—141)

This invention relates to an improved flow-controlling mechanism for two-roll type crusher-feeders for use in reducing and feeding bulk materials, such as ear corn with husks, to feed-grinding mills or other processing machines that require a controlled rate of influx.

One object of this invention is to provide a flow-controlling mechanism for reducing and feeding machines which affords relatively large discharge outlets as compared with conventional ear corn crusher-feeders, so that when handling ear corn with husks, the husks may escape freely instead of accumulating in the reducing chamber and curtailing the output of the reduced material.

Another object is to provide a flow-controlling mechanism that will not be crowded open as a result of the material being forced through the valve by the coacting rolls.

A further object is to provide a valve mechanism that has no valve arms underlying the discharge openings. In conventional earcorn crusher-feeders, husks tend to become entangled on such arms, thereby clogging the valve openings and interfering with the closing movement of the valves.

In the drawings:

Fig. 1 is a plan view of a two-roll type crusher-feeder in which my invention is embodied.

Fig. 2 is a transverse sectional elevation taken on line 2—2 of Fig. 1 with the flow-controlling mechanism partially open to allow the discharge of reduced material, the control handle for the mechanism being omitted.

Fig. 3 is a fragmentary bottom view that corresponds to Fig. 1, some of the parts being broken away to more clearly show the construction of the flow-controlling mechanism.

Fig. 4 is a side view taken from the right of Fig. 1.

Fig. 5 is an enlarged fragment taken from Fig. 2, the valve plates of the flow-controlling mechanism being positioned to completely interrupt the discharge of the reduced material, the relative position of the valve plates being shown in broken lines when the rate of efflux is a maximum.

Fig. 6 is a fragmentary isometric view of a pair of slidably mounted valve plates employed in the flow control mechanism, the broken lines showing the position of the valve plates with respect to each other when the discharge of the material is completely interrupted.

In the drawings the numeral 10 generally designates a rectangular housing which receives the ear corn or material (not shown) that is to be reduced. The housing comprises vertical end walls 11 and sloping side walls 12, the end walls 11 being made to support flanged bearings 13 (Fig. 4) in which a pair of roll shafts 14 and 15 are journaled for rotation in the direction indicated by arrows in Fig. 2. The shafts are made coacting by intermeshing gears 16 mounted on the projecting ends of the shafts, the power being applied to the end 17 of shaft 14.

The roll shafts carry a series of axially spaced teeth

2

18 with formed distal end cutting edges 19 which coact with a centrally disposed shear bar 20, which bar, together with its supporting base 21, spans housing 10 in parallel relation to the axis of the rolls and forms a rigid cross bar element that is adapted to receive impact from the descending teeth on either roll shaft.

Underlying shafts 14 and 15 are elongated discharge outlets 22 and 23 respectively, each outlet being formed on side 24 by base 21 of the central impact-receiving element, on opposite side 25 by the bottom of sloping wall 12, and on the ends by angle-shaped horizontal rails 26 attached to end walls 11.

The flow of reduced material through discharge outlets 22 and 23 is interrupted by rectangular valve plates 27 and 28 respectively, these plates being slidably mounted upon upper faces 29 of rails 26 in overlapping relation therewith as shown in Fig. 4, but their respective ends do not contact the vertical end walls (11, 11) of the housing. When the valve plates are simultaneously moved towards each other in co-ordinated relation, the effluxes from the two discharge outlets are interrupted the same amount, and when the leading edges of the valve plates are positioned in underlapping relation with the base 21 of the impact-receiving element, as shown in Fig. 5, the discharge of reduced material is completely cut off.

The means for actuating valve plate 27 includes a yoke, generally designated as 30 (Figs. 1 and 6), which comprises a pair of arms 31 that are spaced apart and rigidly attached to the plate at right angles to the plate length, and which project horizontally beyond the left side of housing 10. The outer ends of arms 31 are tied together by cross bar 32 to which is secured cam follower 33 positioned on the centerline of the yoke, the cam follower being round in horizontal section and projecting downwardly to engage a cam which will be subsequently described.

The means for actuating valve plate 28 includes a yoke which is generally designated as 34 (Fig. 6), and which includes vertical rib 35 formed integral with the bottom of plate 28. Underlying each end of valve plate 28 and downwardly spaced therefrom is a horizontal arm 36 which is rigidly attached to ends of rib 35 and at right-angles thereto. Yoke arms 36—36 are spaced apart to straddle discharge openings 22—23 and project the same side of the housing as arms 31 of yoke 30, the outer ends being tied together by cross bar 37 which carries cam follower 38 rigidly secured thereto and projecting downwardly therefrom. Cross bar 37 is formed with its middle portion raised to an elevation which positions cam follower 38 in same horizontal plane as cam follower 33 on yoke 30.

The means for simultaneously moving valve plates 27—28 in inverse relation includes oscillatable cam plate 39 having a pair of spiral tracks 40—41 of increasing diameter for engaging cam followers 33 and 38. Cam plate 39 is manually oscillated about a vertical axis by stem 42 fixed thereto and projecting upwardly to receive control handle 43, these oscillatable elements being supported by bracket 44 fixed to either side of the housing. The lower end of the stem seats in aperture 45 in the bracket, and above the bracket is setcollar 46 which supports cam plate 39 in working relation with cam followers 33 and 38. Referring to Figs. 1 and 6, when the cam plate is moved in clockwise direction, the cam followers move towards each other, thereby interrupting the discharge of material through valve openings 22—23, and vice versa. The valve plates and cam followers move in a straight line, valve plate 27 and follower 33 being guided by arms 31—31 of yoke 30 which straddle stem 42 and move in sliding contact therewith. The guiding means for valve plate 28 and follower 38 are

arms 36—36 of yoke 34, these arms being in sliding contact with end walls 11—11 of the housing, or stationary elements supported by the walls.

As the rate of discharge from valve openings 22—23 is increased when valve plates 27—28 are moved away from each other, and as adjacent roll teeth 18 travel concurrently therewith, there is a tendency for the outgoing material to crowd the valve plates open, thereby causing an unwarranted increase in the rate of discharge. To hold the adjusted valve plates against such unwarranted movement, spiral cam tracks 40—41 are made with a rise on the pitch line curve that is relatively small as compared with the distance traveled by each of the cam followers. In other words, the cam tracks are formed to obtain a pressure angle on the pitch line curve that is low enough to hold the cam followers against outward travel. In practice, it is found that this pressure angle should not exceed 8° to obtain the needed locking effect, this angle being measured at any point on the pitch line curve with respect to a tangent and a line normal to a radius passing through the point. To obtain valve openings wide enough to freely discharge reduced earcorn containing husks, without employing an excessively large cam plate, it becomes necessary to make cam tracks 40—41 long enough to afford an oscillatory movement of the cam plate that is in excess of 180°.

In operation the descending teeth on the coating rolls tend to sweep the escaping particles of material angularly through the valve openings in opposite directions away from the central impact-receiving element. The discharge from valve opening 22 is guided in a more downwardly direction by vertical rib 47 (Figs. 5 and 6) carried by valve plate 27, this rib serving as a baffle to deflect the escaping material towards the center of the housing. The rib 35 on valve plate 28 serves the same purpose with respect to the material flowing through valve opening 23. In addition, as ribs 47 and 35 are formed integral with the bottom of their respective valve plates, they also serve as means for strengthening the span of the plates.

It will be further noted that the above described flow-controlling mechanism is workable if the central impact-receiving element, which comprises shear bar 20 and base 21, is eliminated. In this case the leading edges of the valve plates will be in abutting relation when the efflux is completely interrupted.

Although this invention pertains more especially to machines used for crushing and feeding ear corn to feed-grinding mills, it is also adapted for reducing corn cob to a size suitable for litter or mulch, the size being determined by the width of the elongated valve openings which parallel the rolls. The rate of output is, of course, relatively small when producing a small sized product, and vice versa.

What I claim is:

1. In a flow-controlling mechanism for a machine that feeds bulk material, a housing containing material, a pair of outlets in the bottom of the housing, a pair of slidably mounted valve plates for simultaneously interrupting the discharge through the outlets, said interruption being effected when the valve plates move towards each other, a yoke having a pair of arms fixed to each valve plate and projecting to one side of the housing, the arms of one of the yokes being spaced apart and straddling the discharge outlets, a cam follower mounted on the free end of each yoke for movement therewith, means supported by the housing and oscillatable about a vertical axis for moving

the valve plates in inverse relation, said oscillatable means being a cam plate, a pair of spiral tracks of increasing diameter in the cam plate for engaging the cam followers, said tracks being formed in overlapping relation to afford an angular movement of said cam plate that is in excess of 180°, a stem fixed to the cam plate, said stem having a handle for moving the valve plates, and means for guiding movement of the cam followers in a straight line.

2. In a flow-controlling mechanism for a crushing and feeding machine, a housing containing bulk material, a pair of discharge outlets in the bottom of the housing, means for interrupting the two streams of material flowing through the outlets, said means being a pair of valve plates slidably mounted for movement towards each other to effect the interruption, a pair of downwardly coating rolls overlying the valve openings, said rolls having teeth that cast the two streams of material in diverging directions, and means carried by the valve plates for deflecting the diverging streams in a more downwardly direction, said deflecting means being a downwardly projecting baffle positioned substantially below the leading edge of each valve plate.

3. In a flow-controlling mechanism for a feeding machine, a housing containing bulk material, a pair of discharge outlets in the bottom of the housing, a slidably mounted valve plate for each outlet, a yoke having a pair of arms fixed to each valve plate and projecting to one side of the housing, a cam follower mounted on the free end of each yoke for moving the valve plate, means supported by the housing for guiding the movement of the cam followers in a straight line, means supported by the housing and oscillatable about a vertical axis for moving the valve plates in inverse relation, said oscillatable means including a cam plate, a pair of spiral cam tracks of increasing diameter in the cam plate for engaging the cam followers, a handle with stem fixed to the cam plate for adjusting valve plates to obtain a predetermined rate of discharge, and means for holding the adjusted valve plates against unwarranted movement which will increase the predetermined discharge rate, said holding means being the cam tracks formed with a curvature that affords a pressure not exceeding 8° on the cam follower pitch line.
